(Cl. D15—1)

To all whom it may concern:

Be it known that Edward Hugh Clairmonte and Clive Molyneux Clairmonte, subjects of the King of England, and residents respectively of 6 Hunter Road, London S. W. 20, England, and 72 Tetherdown, London N. 10, England, have invented a new, original, and ornamental Design for a Baby's Chair, of which the following is a specification, reference being had to the accompanying drawings, forming part thereof.

We claim:

The ornamental design for a baby's chair, as shown.

EDWARD HUGH CLAIRMONTE.
CLIVE MOLYNEUX CLAIRMONTE.
